UNITED STATES PATENT OFFICE.

BENJAMIN F. SPARROW, OF BOSTON, MASSACHUSETTS.

SCREW-PROPELLER.

SPECIFICATION forming part of Letters Patent No. 394,414, dated December 11, 1888.

Application filed December 1, 1887. Serial No. 256,711. (No model.)

To all whom it may concern:

Be it known that I, BENJAMIN F. SPARROW, a citizen of the United States, and a resident of Boston, in the county of Suffolk and State 5 of Massachusetts, have invented a new and useful Improvement in Propellers for Navigable Vessels, of which the following, taken in connection with the accompanying drawings, is a specification.

10 The object of my invention, which I designate the "centripetal" propeller, is to produce a rotating series of blades or flukes attached by independently curved or sinuous arms to the propeller-shaft in such a manner as to offer the least impediment in their passage through the water, as also to assure an open central space adjacent to the outer end of said shaft to avoid the reaction of the current and consequent production of what is 15 technically known as "dead-water." I attain these results through the novel construction of the sustaining-arms and the angle at which said blades are thereto attached to exert in their rotary motion when submerged a maximum pressure against the water when 20 forging ahead with the least disturbance or "churning" thereof, as also to obtain a like result in reversing the propeller to retard or stop the vessel. The celerity and power I seek 25 cure through the combination of these features become the most essential factors in the avoidance of ocean collisions.

In practical demonstration of the efficiency of my invention I attain greater speed with 30 a medium expenditure of power with a less disturbance of water. I also avoid the strain ordinarily occasioned by the propeller as at present constructed.

A more specific description of my invention, 35 its operation and construction will be observed from reference to the drawings, forming a part of this specification, in which—

Figure 1 illustrates in elevation the general application of my invention as applied to 40 a steam-vessel, Fig. 2 being an end elevation of the propeller, exhibiting the sinuous arms 45 springing from the shaft. Fig. 3 is a transverse section of one of said arms. Fig. 4 indicates in said elevation the flukes placed obliquely to the propeller-shaft; and Fig. 5, a

similar view illustrating one or more flukes attached to a bifurcated shaft, wherein the arms (upon one of which the flukes are broken off) lie parallel.

Similar letters of reference indicate like 55 parts in the several views thereof, referring to which—

A designates the propeller stub-shaft, having connected thereto by suitable devices (not herein shown) the sinuous arms B B, diverging 60 in a manner and for the purpose of forming an open space adjacent to the end of the propeller, as at C. This obviates any reactionary current and permits the flukes D to cut dense water in their rotation without causing the ebullition 65 ordinarily attendant upon screw-propellers. Said flukes D are set at such angle or pitch as will obtain the greatest power with the least disturbance of the medium surrounding them, preferably at an approximating angle 70 of sixty-eight degrees to the plane of their axis, this position assuring the best obtainable results in speed combined with unappreciable jar. Said flukes may be of multiform shape, as I do not confine myself to any particular design so long as I maintain an open center or space near the adjacent ends of the flukes and so adjust said flukes that the water may be cleanly cut at every revolution of the 75 same and freely expelled therefrom. 80

In Fig. 5 I exhibit the supporting-arms B' B² elongated to support two or more flukes placed at divergent angles, as at E' E''. Said shaft is bifurcated from the shoulder A, permitting the arms to be parallel, that the open 85 center may still be preserved, while to insure strength and facilitate the passage of said arms through the water they are double convex in form, as indicated in Fig. 3, the apexes F F separating the element without commotion in the same manner as the flukes. 90

Having described my invention and its operation, what I desire to secure by Letters Patent of the United States is—

1. An improved propeller for navigable vessels, substantially as herein described, having two or more flukes, D, radially extending from bifurcated or sinuous double-convex supports B' B², arranged and constructed to operate in combination with the hub or boss 95 100

of the propeller A in a manner to permit an opening adjacent to said propeller-shaft and to eject the water therefrom.

2. In an improved propeller for navigable vessels, substantially as specified, the stub-shaft A, terminating in bifurcated or sinuous arms B' B'', combined to coact with the parallel or radially-constructed flukes D E' E'',

adapted to secure centrally a rapid and unobstructed expulsion of water from said propeller-shaft.

BENJAMIN F. SPARROW.
